ROTATING PARACHUTE

Edgar G. Ewing, North Hollywood, Calif., assignor to Radioplane Company, Van Nuys, Calif., a corporation of California

Application November 14, 1949, Serial No. 127,143

7 Claims. (Cl. 244—145)

This invention relates generally to parachutes, and relates more particularly to parachutes which rotate when in operation.

It is an object of the present invention to provide a device of this character that is highly efficient.

It is another object of the invention to provide a device of this character which will open slowly, making it suitable for deployment at high velocities.

Another object of the invention is to provide a device of this character having high drag characteristics.

Still another object of the invention is to provide a device of this character that has extremely good directional stability and little or no pendular movement.

A further object of the invention is to provide a device of this character, wherein the opening shock is relatively low.

A still further object of the invention is to provide a device of this character which will automatically spill when it contacts the ground.

Another object of the invention is to provide a device of this character having a relatively small packing volume.

Still other objects of the invention are to provide a device of this character that is relatively light in weight, that requires a minimum of material, and is relatively inexpensive to manufacture.

Other objects and advantages of the invention will appear in the following part of the specification.

Referring to the drawings, which are for illustrative purposes only,

Fig. 1 is a perspective schematic view of a parachute device embodying the invention;

Fig. 2 is a top plan view of the same, showing the canopy fully extended;

Fig. 3 is a sectional view taken on line 3—3 of Fig. 2;

Fig. 4 is a sectional view taken on line 4—4 of Fig. 3;

Fig. 5 is a top plan view of an alternative arrangement; and

Fig. 6 is a sectional view taken on line 6—6 of Fig. 5.

Referring more particularly to Figs. 1 and 2, the device is shown as having a generally circular canopy which comprises a plurality of generally triangular or sector-shaped panels or gores, indicated generally at 10, of suitable material, such as nylon or the like.

Each panel has a slot opening 11 at one side thereof. While said openings may be of any suitable shape, they are shown as being triangular with the outer end of the base 12 of the slot spaced inwardly from the peripheral edge 13 of the canopy, said canopy having a peripheral skirt or skirt portion comprising skirt portions 14 of the panels and there is a radially extending sail 15 for each panel. The skirt portion 14 of each panel defines the base of the slot 11, and the sail 15 defines one side of the slot, the inner edge 16 of said sail being substantially parallel with the outer edge 17, which is also one edge of the panel. The other side of the slot 11 is defined by the adjacent edge of the adjacent panel. The side edges 17 of each panel extend substantially radially and for some purposes a vent opening 20 may be provided at the center of the canopy (Figs. 1 and 2). The peripheral edge 13 of the canopy is reinforced at 21 and the opposite edge of the skirt, defining the base 12, is reinforced at 22. The side edges 17 of the panel are also reinforced as at 23 and the side edges of the sails defining the sides 16 of the opening 11 are reinforced at 24. The reinforcing strips and the

various parts of the canopy are sewed together or otherwise suitably secured.

Suspension lines 30 are provided and, as shown in Figs. 1 and 2, extend along the radial edges 17 of the panels where they are secured by sewing or other suitable means, the lower ends of said lines 30 being secured to a swivel unit 31 to which a load 32 may be attached. The load 32 may be a missile, supplies or the like which are to be dropped to the ground, or a person. In the latter case the harness of the parachuter is attached to the swivel 31.

The parachute may be packed in a very small package due to the fact that there are cutout areas 11, which reduces the amount of material in the canopy and also results in a reduction in the weight of said canopy.

In operation, as when the device is lowering a load, the canopy rotates in the direction indicated by the arrows 33 in Figs. 1 and 2. This rotation is effected by the sails 15, the edges 16 of which flare outwardly, as at 35 in Figs. 3 and 4, thereby causing said sails to assume a blade-like shape and causing said sails to function as airfoils. The edges 17 of the blades are held against flaring by the suspension lines 30 which run along said edges 17 and are suitably secured to the canopy.

The rapid rotation of the canopy substantially increases the efficiency thereof, and the device has a gyroscopic effect which materially increases the directional stability of the device and materially reduces or substantially eliminates pendular movement thereof.

Another advantage of the invention is that it may be used in connection with high velocity missiles, to slow down and land same. The parachute will open relatively slowly and the opening shockloads are minimized due to the lattice-like effect of the canopy. It has also been found that there is automatic spilling or collapsing of the canopy as soon as it contacts the ground, thereby avoiding dragging of the load at the end of the descent.

Referring to Figs. 5 and 6, the canopy of this arrangement of a parachute is also of generally circular shape and comprises a plurality of generally triangularly or sector-shaped panels or gores 10.

The apices of the panels 10 are secured to a circular piece 40 (Fig. 5) by sewing or other suitable means and each panel has a four-sided slot opening 11a, which is wider at the outer end than at the inner end 41, the outer end being spaced inwardly from the peripheral edge 13 of the canopy. Each panel has an outer or skirt portion 14, and the inner side edge 42 thereof defines the outer end of the slot 11a. A sail 15a has a side 43 which defines the adjacent longitudinal side of said slot, a side of the slot opposite the sail being defined by the adjacent panel 10.

The side edges of the panel 10 extend substantially radially and the side edges 43 of the sails are also on a radius so that the inner ends of said sails are narrower than the outer ends. Thus it will be apparent that the sails and the slots may be varied in shape without departing from the essence of the invention.

The peripheral edge of the canopy is reinforced by strips of suitable fabric material or the like, said strips being indicated at 45, and the radial side edges of the panels 10 are also similarly reinforced, as at 46.

The panel edges 41, 42 and 43 are also reinforced by strips 47, all of the various strips above mentioned being sewed to the panels or otherwise suitably secured.

In the arrangement of Fig. 5, the suspension lines 30a do not extend to the central part of the canopy as in the arrangement shown in Figs. 1 to 4, but have their end portions 30b secured to the sides of the panels along the outer end portions of said sides, the reinforcements 46 serving as extensions of said lines so that the sails 15a will take on an airfoil shape when the device is in operation, as is the case of the sails 15 of the arrangement shown in Figs. 1 to 4 inclusive.

The shape of the sails 15a under these conditions is shown in Fig. 6 and differs somewhat from the shape of the sails 15 (Fig. 3) under operating conditions, but with either sail arrangement the object and advantages of the invention will be attained.

80 I claim:

1. A parachute device, comprising: a canopy of gen-

erally circular shape and comprising a plurality of generally triangular shaped panels secured together along adjacent edges, said canopy having a vent opening in the center, each of said panels comprising a skirt portion at the outer end thereof and a generally radially extending sail intermediate the ends and along one side of the panel, the sails of the canopy being annularly spaced apart and facing in the same peripheral direction; a plurality of suspension lines depending from the canopy and including portions extending along the edges of the panels whereat the sails are disposed, and secured in position; and a swivel unit secured to the lower ends of the suspension lines.

2. In a parachute device: a generally circular canopy having a peripheral skirt from which extend inwardly a plurality of generally radial sails, said sails being substantially uniformly arranged and spaced apart and being relatively narrow along a dimension parallel to the air flow and of small curve or bow in cross-section; and a plurality of holding means for corresponding edges of said sails, said means including at least a portion of respective suspension lines.

3. In a parachute device: a generally circular canopy having a peripheral skirt of substantial width from which extend a plurality of generally radial sails, said sails being substantially uniformly arranged and being relatively narrow and facing in the same direction and having substantially the same pitch; a plurality of suspension lines, a portion of each suspension line extending along at least a portion of one edge of the respective sails and secured thereto; and a swivel device secured to the lower ends of said suspension lines.

4. A canopy for a parachute device, comprising: fabric material of generally circular shape, having a peripheral skirt portion, said canopy having openings therein to provide a plurality of relatively narrow, elongated, generally radially extending sails annularly spaced apart, one edge of each of said sails being adapted to balloon outwardly, said openings being wider at their outer ends and said edges of said sails being at the corresponding sides thereof.

5. A parachute device, comprising: a generally circular canopy formed of a plurality of generally triangular shaped panels marginally secured together, each of said panels having a generally triangularly shaped opening therein of substantially fixed area with the base at the outer end and spaced inwardly a substantial distance from the outer edge of the panel in substantially parallel relationship so that the canopy has a distinct, relatively wide peripheral skirt portion of relatively uniform width, the respective portions of said panels along one side of the respective openings and substantially contiguous therewith forming elongated generally radial sails facing in the same peripheral direction and uniformly spaced apart,

said sails being relatively narrow along a dimension parallel to the air flow and of small curve in cross-section giving said sails a low angle of attack; and a plurality of suspension lines depending from the canopy and including portions extending along the edges of the panels whereat the sails are disposed.

6. A parachute device, comprising: a generally circular canopy formed of a plurality of generally triangular shaped panels marginally secured together, said canopy having a vent opening in the center, each of said panels having a generally triangularly shaped opening therein of substantially fixed area with the base at the outer end and spaced inwardly a substantial distance from the outer edge of the panel in substantially parallel relationship so that the canopy has a distinct, relatively wide peripheral skirt portion of relatively uniform width, the respective portions of said panels along one side of the respective openings and substantially contiguous therewith forming elongated generally radial sails facing in the same peripheral direction and uniformly spaced apart, said sails being relatively narrow along a dimension parallel to the air flow and of small curve in cross-section giving said sails a low angle of attack; a plurality of suspension lines depending from the canopy and including portions extending along the edges of the panels whereat the sails are disposed, and secured in position; and a swivel unit secured to the lower ends of the suspension lines.

7. A canopy for a parachute device, comprising: fabric material of generally circular shape having a plurality of annularly spaced openings of substantially constant area, the outer ends of said openings being substantially wider than the inner ends and spaced inwardly a substantial distance from the peripheral edge of the fabric material and generally parallel therewith thereby providing a relatively wide skirt; and a plurality of generally radially extending annularly spaced sails between said openings.
